Term of patent 14 years

(Cl. D55—1)

Des. 201,577

PAGE 2

FIG. 2

FIG. 3

FIG. 1 is a perspective view of a shape cutting machine embodying our new design;

FIG. 2 is a plan view thereof;

FIG. 3 is a front elevational view thereof;

FIG. 4 is a rear elevational view thereof;

FIG. 5 is an elevational view thereof as seen from the right indicated by line 5-5 of FIG. 4; and

FIG. 6 is an elevational view thereof as seen from the left as indicated by line 6-6 of FIG. 4.

The broken line showing of a supporting frame, cutting torch and carrier and an operator in FIG. 1 is for illustrative purposes only.

We claim:

The ornamental design for a shape cutting machine or similar article, as shown and described.
